UNITED STATES PATENT OFFICE.

MARY C. SHAVER, OF ELGIN, ILLINOIS.

DESIGN FOR A BADGE.

SPECIFICATION forming part of Design No. 21,951, dated November 1, 1892.

Application filed September 2, 1892. Serial No. 445,587. Term of patent 3½ years.

To all whom it may concern:

Be it known that I, MARY C. SHAVER, a citizen of the United States, residing at Elgin, in the county of Kane and State of Illinois, have 5 invented a new and original Design for Pins, Badges, &c., of which the following is a specification.

My invention relates to a design for badges, the same consisting of a new and original arrangement and configuration, as shown in the 10 accompanying drawing, in which is illustrated a badge bearing a design involving my invention.

Referring to the drawing, the central object 15 in the design is a representation of the earth, showing pictorially North and South America, with the Atlantic and Pacific oceans upon opposite sides thereof. Adjacent to this central

figure, upon opposite sides, are seen the American and Spanish flags, and above the central 20 figure and connecting said flags is an arched scroll having a scalloped upper edge or border. Below the central figure and as though bearing the earth is the American eagle, in whose bill is seen a scroll. 25

Having thus described my invention, I claim—

The design for a badge, substantially as herein shown and described.

In testimony that I claim the foregoing as 30 my own I have hereto affixed my signature in the presence of two witnesses.

MARY C. SHAVER.

Witnesses:

C. A. LAWSON,
F. W. JOSLYN.
